UNITED STATES PATENT OFFICE.

MOSES S. WALTON, OF LOS ANGELES, CALIFORNIA.

DESIGN FOR A FARM-TRACTOR BODY.

46,709.

Specification for Design.

Patented Nov. 24, 1914.

Application filed August 19, 1913. Serial No. 785,565. Term of patent 7 years.

To all whom it may concern:

Be it known that I, MOSES S. WALTON, a citizen of the United States, residing at Los Angeles, in the county of Los Angeles, State of California, have invented a new, original, and ornamental Design for Farm-Tractor Bodies, of which the following is a specification, reference being had to the accompanying drawing, forming a part thereof, and in which—

Figure 1 is a plan view and Fig. 2 is a side elevation of my farm tractor bodies.

I claim:

The ornamental design for a farm tractor body, as shown.

MOSES S. WALTON.

Witnesses:

R. S. BAUM,
W. MARVIN SPEARS.
